Primary Examiner — Vy N Koenig(74) *Attorney, Agent, or Firm* — Jefferson IP Law, LLP; Raymond B. Persino(57) **CLAIM**

The ornamental design for a webcam cover, as shown and described.

DESCRIPTION

FIG. 1 is a perspective view of a webcam cover, showing a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a perspective view thereof showing the webcam cover in an alternative configuration.

The broken lines in the drawings depict portions of the webcam cover that form no part of the claimed invention.

1 Claim, 5 Drawing Sheets(56)
